PRODUCTION OF VISCOSE RAYON THREADS,
FIBERS, FILAMENTS, AND THE LIKEHorace Bartlett Merriman, New Malden, England,
assignor to Courtaulds Limited, London, England,
a British companyApplication January 9, 1952, Serial No. 265,677
In Great Britain January 23, 1951

1 Claim. (Cl. 68—209)

1

This invention relates to the production of viscose rayon threads, fibres, filaments, and the like continuous filamentary materials hereinafter generally referred to as "threads," and is particularly concerned with the recovery of carbon disulphide from such threads during their manufacture. The term "thread" also includes thick tows of filaments such as are normally built up for the production of staple fibres.

In the spinning of viscose the acid coagulant bath decomposes a large percentage of the xanthate residues present in the viscose to carbon disulphide which is carried over by the thread to subsequent processing stages. Proposals have already been made for recovering such carbon disulphide from the threads. Thus British Patent Specification No. 170,817 describes a process in which the carbon disulphide is evaporated from the thread by passing it through a hot water bath beneath a canopy, the edges of which are immersed in the hot water so that the liberated vapours may be collected by a pipe and liquefied.

In United States patent specification No. 2,451,890 it is proposed to pass the thread through a tank of hot water under a bell-like cover, the edges of which are immersed in the liquid and to collect the vapours under their own pressure, the thread continuously entering the tank at one end and leaving it at the other end after having been conveyed progressively through the bath over rollers, plates or between perforated partitions, beneath the bell-like cover.

It is known that carbon disulphide vapour and air form an explosive mixture. Carbon disulphide vapour is also highly objectionable to operatives so that it should not be allowed to escape and pollute the atmosphere of the spinning shop. Prior proposals for carbon disulphide recovery have not been entirely satisfactory from these points of view.

The object of the present invention is to facilitate the threading up of a carbon disulphide recovery plant.

In accordance with the present invention, apparatus for the recovery of carbon disulphide from viscose rayon threads comprises a container for a heated liquid which is fitted with a continuous channel around its upper edge, also for containing a liquid, a bell mounted over the container so that it can be raised and lowered and so that, when in its lowest position, its edges will be immersed in liquid in the continuous channel to seal off the container, the bell having thread-entrance and thread-exit ducts so constructed that when the bell is in its lowest position the

2

lower edges of the ducts are immersed in the heated liquid in the container and the ducts are thereby sealed off, conveying mechanism fitted to the bell for passing the thread through the container and means for withdrawing carbon disulphide vapours from within the bell.

Examples of suitable heated liquids are water, a spinning bath liquid and aqueous ammonium sulphate solution. The liquid for use in the channels is preferably cold water or cold liquors collected from godets and the like and known generally as "channel liquor."

The conveying mechanism preferably consists of two groups of freely-mounted or stationary rollers with their axes parallel and one group at each end of the bell. Threads when treated with hot liquid may tend to shrink and the use of freely mounted rollers ensures that their rotation is effected solely by the travelling thread and, as a result, the thread is not submitted to any undue tension or strain during the hot liquid treatment.

In a preferred form of apparatus, two threads are treated simultaneously by using a large tank having a continuous peripheral channel and a central channel, joined at its ends with the peripheral channel, dividing the tank into two recovery zones. The central channel preferably has a partition attached to it to assist in dividing off the two recovery zones. Each of the two zones has its own bell, conveying mechanism and plant for removing and recovering carbon disulphide from within the bell.

A specific example of an apparatus constructed in accordance with the present invention is illustrated in the accompanying drawings, in which,

Figure 1 is a plan view showing a single bath comprising two recovery units, the bell of one unit being removed to show details within the tank,

Figure 2 is a section through line 2—2 of Figure 1, and

Figure 3 is a section through line 3—3 of Figure 1.

Referring to the drawings, a trapezoidal tank 1 has a continuous channel 2 around its periphery and is divided down its centre by a similar channel 3, connected at its ends to the channel 2. A vertical partition 4 extends downwardly from the channel 3 for about half the depth of the tank 1. The tank 1 is thus divided into two identical recovery units 5, 6 each of which has a continuous channel surrounding its periphery, the channel 3 being common to both units. In operation, the tank 1 is nearly filled with hot

3

water or other liquid supplied from pipes 7, 8 while the channels 2, 3 are filled with a cold liquid. In the following description, only unit 5 will be described in detail but it will be understood that unit 6 is constructed in the same way and like numerals are included in the drawings to indicate like parts.

A bell 9, which completely covers the unit 5, has a peripheral lip 10, which, when fitted into the liquid in the channels 2, 3 as shown, forms a gas-tight seal. The bell 9 can be raised and lowered, for example, by an overhead crane 28 hooked into eyes 26, 27. The bell 9 has a funnel-shaped opening 11 and a similarly shaped opening 12 by which the tow enters and leaves respectively, the recovery unit; both openings 11, 12 are wide enough to admit the hand. In operation, the lower edges of the openings 11, 12 are both immersed in the liquid in the tank 1 so that the openings are also sealed off. Two sets of fixed dollies or rollers 13, 14 are suspended from the underside of the bell 9 by two holders 13A, 14A, close to the openings 11, 12 respectively. The bell 9 also has a trap 24 in which carbon disulphide vapours collect and are drawn away through a pipe 25 to a recovery plant (not shown).

The unit 5 is operated as follows:

To start up, the bell 9 is raised and a tow 15 of freshly-extruded viscose filaments is passed by hand through the opening 11, round the rollers 13, 14 as shown particularly in Figure 1, and then out through the opening 12. The bell 9 is now lowered on to the tank 1 so that the tow 15 is immersed in the liquid in the tank, the peripheral edge 10 of the bell is immersed in the channels 2, 3 to seal off the bell and the lower edges of the openings 11, 12 are immersed in the liquid in the tank to seal off these openings. At the entrance end, the tow 15 passes over a roller 16 into the bath and at the exit end it passes over rollers 17, 18, 19 on its way to the staple fibre cutter (not shown); the rollers 17, 18, 19 serve to remove excess liquid from the tow, the excess liquid draining back into the tank through the opening 12. As the tow passes through the hot liquid, carbon disulphide associated with it is vapourized, collected in the trap 24 and re-

4

covered by way of the pipe 25; any bubbles of gas formed near the openings 11, 12 are directed towards the centre of the tank 1 by guides 20, 21 which are provided with slots 22, 23 respectively to allow passage of the tow 15. If desired a lid may be placed over the tank 1 during the setting-up operation.

With the machine according to the invention, the sealing of the bell during passage of the tow remains unbroken so that there is no mixture of air and carbon disulphide vapour formed during actual recovery operations.

What I claim is:

Apparatus for the simultaneous recovery of carbon disulphide from two viscose rayon threads comprising a container for a heated liquid, a continuous channel, also for containing liquid, fitted around the upper edge of said container, a central channel joined at its ends with the peripheral channel and dividing the container into two recovery zones, and in each of the two recovery zones, a bell mounted over the container to cover the recovery zone, means for raising and lowering said bell, the bell being so dimensioned that in its lowest position its edges will be immersed in liquid in the continuous channel formed by the central channel and half the peripheral channel on the container, whereby the container may be sealed off in both recovery zones, thread entrance and thread exit ducts within the said bells so constructed that when the bells are in their lowest positions the lower edges of the ducts will be immersed in the heated liquid in the container whereby the ducts are sealed off, conveying mechanism fitted to the inside of said bells for passing two threads through the container, and means for withdrawing carbon disulphide vapours from within the two bells.
